UNITED STATES PATENT OFFICE.

ALBERT WARD PATTISON, OF LOCKPORT, NEW YORK, ASSIGNEE OF ONE-HALF TO
HARRY PORTER DUQUETTE, OF LOCKPORT, NEW YORK.

VAPORIZER HYDROCARBON-BURNER.

1,202,755.

Specification of Letters Patent. Patented Oct. 24, 1916.

Application filed April 22, 1916. Serial No. 93,012.

To all whom it may concern:

Be it known that I, ALBERT WARD PATTISON, a citizen of the United States, residing at Lockport, in the State of New York, 5 United States of America, have invented certain new and useful Improvements in Vaporizer Hydrocarbon-Burners, of which the following is a specification.

This invention relates to improvements in 10 burners particularly adapted to be utilized with hydrocarbon fuel in stoves, heaters and the like, and the objects of the invention are to facilitate in vaporizing the fuel and effectively mixing therewith a predetermined 15 and desired proportion of air so obtaining a better efficiency, to simplify the construction of the burner and generally to adapt the several parts to better perform the functions required of them.

20 With the above objects in view, the invention consists essentially of the improved construction particularly described and set forth in the following specification and accompanying drawings forming part of the 25 same.

In the drawings, Figure 1 is a perspective view of the improved burner with one 30 of the dome covers removed and as seen when mounted in a stove, the front and top 35 of stove being shown in dotted lines. Fig. 2 is a longitudinal section of the improved burner. Fig. 3 is a transverse section of one 40 of the dome covers. Fig. 4 is a longitudinal section of an alternative form of dome cover. Fig. 5 is a transverse sectional view through 45 one of the burners.

Like characters of reference refer to like 50 parts in the several figures.

Referring to the drawings, A represents 55 the improved burner comprising the base plate 10 provided with a plurality of orifices 11 therethrough preferably arranged in pairs and between which wells or depressions 12 are located. These wells are provided with concentrically arranged and upwardly disposed conical jets 13 having orifices 14 therethrough operatively connected to the branch pipes 15 threaded or otherwise secured therein, which pipes are in turn operatively connected through the feed pipe 16 with the oil reservoir 17 which is normally located above the burner so that the oil is fed thereto under gravity.

Around the edge of the base plate 10 and 60 the orifices 11 the beadings or shoulders 18 ex-

tend which are formed integrally with the base plate and surround the orifices individually and in pairs and the central wells 12 therebetween, the shoulders being adapted to engage with the outer periphery of the lower ends of the dome covers 19 and retain the same in place. These covers are substantially D-shaped in section and provided with entirely closed solid back and sides, and outlet spaces 24, the back having a pair of notches 20 adapted to bridge and embrace the shoulders 18 and the said domes are further formed with a passageway 21 forming a concentrically arranged conduit 22 located above the conical burners 13. It will thus be seen that the outer walls of the passageway 21 form with the inner periphery of the dome covers 19 air inlet conduits 23 which are located above the orifices 11.

In Fig. 4 an alternative form of dome 75 cover is shown differing from that already described only in the fact that outlets 24 are provided both in the back and front thereof. Although this type of burner is generally arranged to be slidably mounted 80 in a stove or other heater it may also be formed with a downwardly disposed flange 25 integral with the bottom thereof and arranged so that it may form a support should such be found necessary or convenient. 85

The assembly of the burner will be readily understood from the foregoing description.

When the burner is in use the wells 12 are filled with oil which is lighted whereupon oil is fed under gravity from the reservoir 17 through the pipe 16 and is delivered to the branch pipes 15 from whence it passes through the orifices 14 of the burner. The current of air which is induced through the ordinary chimney draft passes through the orifices 11 to the conduits 23 and thence through the concentrically arranged conduit 22 where meeting with the fuel delivered through the orifice 14 it intermixes with the same giving the necessary combustion. The products of combustion pass through the openings 24 in the front of the dome covers 19 and passing over the top of the said dome effectively 100 heat the stove in which the burner is mounted.

When the type of dome cover illustrated in Fig. 4 is utilized it will be understood that the products of combustion pass on 110

both sides of the dome cover and over the top of the adjacent cover, giving the desired heating effect to the stove.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

In a burner of the class described and in combination, a base plate having a plurality of orifices therethrough arranged in pairs with a well between each pair, shoulders

formed integrally with the base plate, said shoulders surrounding the orifices individually and in pairs and the central well therebetween, conical jets in the wells, and dome covers provided with air conduits fitting over the orifices in the base plate and having a concentrically arranged discharge conduit located above the jets, the back of the dome covers being closed and formed with notches therein engaging with the said shoulders, and a discharge opening in the front of the dome covers, as and for the purpose specified.

In witness whereof I have hereunto set my hand.

ALBERT WARD PATTISON.
